CLAIM

The ornamental design for a translation wheel, as shown and described.

DESCRIPTION

FIG. 1 is a front perspective view of a translation wheel;

FIG. 2 is a front view thereof;

FIG. 3 is a back view thereof;

FIG. 4 is a right side view thereof;

FIG. 5 is a left side view thereof;

FIG. 6 is a bottom side view thereof; and,

FIG. 7 is a top side view thereof.

Note that any broken line illustration of environmental structure in the drawing is not part of the design sought to be patented.
